UNITED STATES PATENT OFFICE.

JAMES E. DUFFY, OF CHICAGO, ILLINOIS.

WHIP-LOCK.

965,696.

Specification of Letters Patent. Patented July 26, 1910.

Application filed May 18, 1910. Serial No. 561,952.

To all whom it may concern:

Be it known that I, JAMES E. DUFFY, a citizen of the United States, residing at Chicago, in the county of Cook and State of

5 Illinois, have invented new and useful Improvements in Whip-Locks, of which the following is a specification.

This invention relates to whip locks, the object being to provide a whip socket with 10 a locking device whereby the whip may be readily locked in place in the whip socket so that unauthorized persons will not be able to remove the whip, at least without the exercise of a great deal of skill and manipulation in breaking the lock.

To such ends this invention consists in certain novel features of construction and arrangement, a description of which will be found in the following specification and 20 the essential features of which will be more definitely pointed out in the claims appended hereto.

The invention is clearly illustrated in the drawing furnished herewith, in which—

25 Figure 1 is a central longitudinal section through a whip socket showing in front elevation, my locking device and a fragment of a whip secured in the socket by means of said locking device, Fig. 2 is a central longitudinal section of the whip socket taken on the line 2—2 of Fig. 1 and showing the locking device in side elevation and the whip in a position about to be connected with the locking device, Fig. 3 is a horizontal section on the line 3—3 of Fig. 1 and Fig. 4 is a central longitudinal section through a fragment of a whip socket showing in side elevation a fragment of a whip and whip lock in a slightly modified form.

40 Referring to the drawings, an ordinary whip socket A, will be seen which is tubular in form having a closed bottom α . A fragment of a whip B, is shown as secured in the socket by means of my improved locking device C. In the preferred form said locking device comprises a curved plate 10, secured in the whip socket and a pin or stud 11, secured to the lower end of the whip stock and adapted to be locked to said plate. The 45 plate 10, is semi-circular in form and practically fits against the inner face of the whip socket and is secured in place therein, as for instance by means of a pin or nail 12, extending through the adjacent walls of the 50 plate and socket and a tongue 13, at the lower end of the plate which passes through

the bottom α , of the socket and is headed thereon. Any other suitable form of connecting means may be employed for securely fastening the plate to the whip socket.

60

The plate 10, is formed with a trackway 14, of irregular form and as shown said trackway comprises an irregular shaped slot having an entrance at 15, through which the locking pin 11, may enter the irregular slot 65 to lock the whip in place in the socket. No particular form of arrangement of irregular slot is essential, but the one I have shown is extremely intricate and difficult to follow when it is hidden from view, as it is while 70 covered up by the wall of the whip socket. From the entrance opening 15, said slot has an upwardly extending portion 16, terminating in a notch 17, extending toward the right. Slightly above the point of entrance 75 15, the slot runs to the left as at 18, then down as at 19, to a horizontal portion 20, which terminates in a downwardly extending and right angled portion 21, 21^a. In the horizontal portion 20, is a downwardly opening notch 22, and opposite a tongue 23, is an upwardly extending portion 24, which leads to another horizontal portion 25, containing offset portions 26, 27. Extending up from said horizontal portion 25, is another vertical extension 28, which terminates in a horizontal portion 29, having vertically 80 extending notches 30, 31, that extend in opposite direction from said horizontal portion 29.

90

The pin or stud 11, may of course be secured in the whip stock in any desired manner, as for instance it may be screwed therein, and projects beyond the face of the whip stock sufficiently to form a firm bearing on 95 the marginal edges of the irregular slot 14, in the plate 10.

The whip is locked in place by inserting it into the socket, bringing the pin or stud 11, down along the edge c , of the plate 10, 100 and then turning it around toward the left, as viewed in the drawing, and bringing it up into the entrance 15, of the irregular slot 14. The pin may then be moved through said slot into any one of the recesses 105 thereof and I have shown the pin in the end of the horizontal offset portion 26. To detach the whip, the pin should be moved in the direction taken by the arrows in Fig. 1. It is obvious that when said plate 10, is 110 covered by the wall of the whip socket, it is an exceedingly difficult matter to trace the

direction which the pin should take in removing it from the irregular slot in view of the many turns and abutments with which it comes in contact in moving about in the 5 irregular slot. One knowing the shape of said slot may, however, easily follow the same and quickly bring the pin to the entrance opening 15, after which the whip may be withdrawn. For the guidance of 10 the owner a mark D, is placed upon the whip, which mark indicates, by reason of its position relative to the upper edge of the whip socket, the exact location of the pin 11, in the irregular slot 14. With this guide 15 before him the owner can more readily locate the position of the pin and guide it out of the slot. For his further guidance, a card may be printed, bearing a facsimile of the slot in the plate, which card may be 20 used by the owner to guide him in moving the pin out of its locked position.

The edge C¹, of the locking plate opposite the entrance 15, is straight and unbroken, so that the user may slide the pin 11, along this 25 edge when he wishes to have the socket support the whip without locking it, the whip being then free to be withdrawn at any time, as for instance when he wishes to have the whip in readiness for use.

30 In the modified form shown in Fig. 4 the curved plate C¹, is shown as secured to the whip stock B¹, and the pin 11¹, secured in the wall of the whip socket A¹, so as to project into the socket or hollow thereof. The irregular slot 14¹, of any suitable shape is 35 formed in the plate C¹, and the operation of locking or unlocking the whip is substantially the same as that of the preferred form.

I am aware that various alterations and 40 modifications of this device are possible without departing from the spirit of my invention, and I do not therefore desire to limit myself to the exact form of construction and arrangement shown and described.

I claim as new and desire to secure by 45 Letters Patent:

1. A whip lock comprising in combination, a whip socket, a whip, a plate having an irregular trackway therein and secured to one of said members and a projection secured to the other of said members and adapted to seat in said irregular trackway of the plate to lock the whip in the socket. 50

2. A whip lock comprising in combination, a whip socket, a whip, a plate of semi-circular form secured to said whip socket and having an irregular slot formed therein, comprising vertical and horizontal offset portions and an entrance opening, and a projection on the whip adapted to be moved 55 into said slot to lock the whip in the socket. 60

3. A whip lock comprising in combination, a whip socket, a whip, a curved plate secured in said whip socket and having a slot of irregular form comprising an entrance opening and a continuous slot having 65 offset notches extending back therefrom, and a stud projecting from the whip and adapted to be inserted in said slot to lock the whip in the socket. 70

4. A whip lock comprising in combination, a whip socket, a whip, a curved plate secured in said whip socket and having a slot of irregular form comprising an entrance opening and a continuous slot having 75 offset notches extending back therefrom, a stud projecting from the whip and adapted to be inserted in said slot to lock the whip in the socket, and a mark upon said whip for determining the location of said pin in the 80 slot.

In witness whereof I have hereunto subscribed my name at Chicago, Cook county, Illinois, this 16th day of May 1910.

JAMES E. DUFFY.
